UNITED STATES PATENT OFFICE.

EDWARD S. WINCHESTER, OF DORCHESTER, MASSACHUSETTS.

KNOB ATTACHMENT.

SPECIFICATION forming part of Letters Patent No. 416,310, dated December 3, 1889.

Application filed February 15, 1889. Serial No. 300,076. (No model.)

To all whom it may concern:

Be it known that I, EDWARD S. WINCHESTER, of Dorchester, in the county of Suffolk and State of Massachusetts, have invented 5 certain Improvements in Door-Latches, of which the following is a specification.

The object of my invention is to provide for the ready connection and disconnection of the knobs and knob-spindle, and to prevent 10 looseness or rattling of the parts when in operative position.

To this end it consists in a peculiar construction and arrangement of parts, having as its basis a knob-shank toothed to interlock 15 with the usual hub or tumbler by which the latch is operated, as hereinafter explained in detail.

In the drawings I have illustrated my invention as applied to a rim-latch; but it is to 20 be understood that it may be applied in like form and manner to the mortise-latch.

In the accompanying drawings, Figure 1 is a vertical transverse section through a latch provided with my improvements. Fig. 2 is 25 an outline view showing the manner in which the knobs are unlocked. Fig. 3 is a perspective view of the knob-spindle and co-operating parts.

Referring to the drawings, A represents a 30 latch-case, having, as usual, the inner and outer walls a and a' , and also having on one side a tubular sleeve or projection a^2 .

B represents the usual hub or tumbler for operating the latch-bolt. It is sustained with- 35 in the case by the side journals $b b'$, as usual, and is provided on one side with a projection b^2 , extending into the sleeve a^2 of the case, and toothed or notched at the outer end, as shown.

C represents the inner knob, having a shank c inserted within the sleeve a^2 of the case, and toothed at its end to interlock with the hub B. When the parts are interlocked, the 40 movement of the hub. By moving the knob end- wise it may be disengaged from the hub, so as to turn independently.

D represents the outer knob, rigidly and 45 permanently affixed to one end of the spin- dle, which has a square or angular portion d and a threaded extremity d' .

E represents a strong spiral spring, which is slipped over the spindle and against the outer knob D. The square portion of the spindle is passed through the hub B, and its 55 threaded end screwed into the knob C. The spring acting between the hub and the outer knob D urges the spindle outward in the di- 60 rection indicated by the arrow in Fig. 1, and the spindle in turn acts to draw the inner 65 knob toward the case, so as to keep its toothed or serrated end in engagement with the hub, as shown in Fig. 1. When the parts are thus interlocked, the rotation of either knob serves 70 to turn the hub, which is prevented from ro- 75 tating on the spindle by reason of the angu- lar form of the latter serving to prevent the rotation of the inner knob C upon the spin- dle, and thus prevents the parts being sep- arated.

In order to remove the knobs, it is only necessary to push axially on the outer knob D with force sufficient to compress the spring. The effect of this action is to push on the 80 spring endwise and carry the inner knob C 75 out of engagement with the hub B, as indicated in Fig. 2. This leaves the inner knob free to be unscrewed from the spindle, after which the latter may be withdrawn in an end- wise direction.

In assembling the parts the spindle with the spring thereon is first inserted and the spring compressed, after which the knob-seat is screwed inward to the required point. The 85 knob B is then relieved from pressure, and the reaction of the spring causes the inter- locking of the knob and hub.

It will be observed that under my construc- 90 tion the spring is the only piece used in ad- dition to those ordinarily employed in spring- latches. It will also be observed that the 95 spring serves not only to maintain the con- nection of the parts, but to hold the parts snugly to their places, so that there can be no play or rattling of the knob in an endwise direction in relation to the hub.

I commonly construct the inner knob with an annular flange c^3 , fitting over and around the end of the sleeve a^2 , and this in order to improve the appearance of the latch and to 100 prevent the fingers from being caught be- tween the knob and the sleeve.

Having thus described my invention, what I claim is—

1. In combination with the latch-case and the latch-operating hub toothed at one side, the axially-movable inner knob toothed to engage the hub, the outer knob and its spindle having the angular and the threaded portions seated in the hub and the inner knob, respectively, and the spring acting to urge the spindle endwise in an outward direction.
2. In combination with the latch-operating hub toothed on one side, the knob toothed to interlock therewith, and an axially-movable

spindle having an angular portion seated in the hub and a threaded end screwed into said knob, whereby the said knob may be locked and unlocked by moving the spindle endwise from the opposite side of the case. 15

In testimony whereof I hereunto set my hand, this 18th day of December, 1888, in the presence of two attesting witnesses. 20

EDWARD S. WINCHESTER.
